UNITED STATES PATENT OFFICE.

HUGO E. GRIESHABER, OF GROTON, CONNECTICUT, ASSIGNOR TO ELECTRIC BOAT COMPANY, A CORPORATION OF NEW JERSEY.

VALVE MECHANISM FOR SUBMARINES.

1,417,165.

Specification of Letters Patent. Patented May 23, 1922.

Application filed November 10, 1920. Serial No. 423,024.

To all whom it may concern:

Be it known that I, Hugo E. GRIESHABER, residing at Groton, in the county of New London, State of Connecticut, have invented 5 certain new and useful Improvements in Valve Mechanism for Submarines; and I do hereby declare the following to be a full, clear, and exact description of the invention, such as will enable others skilled 10 in the art to which it appertains to make and use the same.

This invention relates to valve mechanism for submarine vessels.

When it is desired to submerge a submarine, the common practice is simply to open 15 the series of flooding valves situated in the bottom of the hull, and thus allow the water to flow into the ballast tanks. This method has proved satisfactory when the 20 vessel is at rest or cruising at very low speeds, but when going at full speed the time required to fill the tanks and effect submergence is greatly increased, due to the inertia of the water and its consequent failure 25 to flow into the tanks of the rapidly moving vessel. Obviously this is a serious disadvantage. The consequence is that either the speed must be slackened, or full speed maintained and the time of sub- 30 mergence prolonged—both undesirable and possibly dangerous alternatives. It is very important as a military requirement that the vessel go from full speed on the surface to full speed submerged in the shortest possible 35 time, and to this end this invention has been developed.

The invention in its simplest form comprises the combination of a scoop with the flooding valve in such a manner that when 40 the valve is open the scoop is simultaneously thrown into operative position facing the direction in which the vessel is moving. The forward movement of the ship thus tends to scoop up the water and force it 45 through the valve passage and into the ballast tanks. Submergence can be effected by this means even more quickly during fast cruising than when at rest.

In order that the invention may be 50 more clearly understood reference is had to the accompanying drawings disclosing two preferred embodiments thereof, and in which Figure 1 is a longitudinal section through the hull of a submarine, and show-

ing the flooding valve mechanism, and Fig- 55 ure 2 is a section similar to that of Fig. 1 but showing a modified type of valve.

In these drawings 1 represents the hull of the vessel and 2 the flooding passage therein leading to the ballast tanks. When 60 using the type of valve shown in Fig. 1 a frame or housing 3 is secured to the inner side of the hull and surrounds and defines the flooding passage. The inner side of this housing terminates in an annular valve seat 65 4 upon which the valve 5 is designed to be seated. The peripheral face of the valve is provided with a gasket 6 adapted to bear against the valve seat and assure a watertight joint. The valve is operated by means 70 of the valve stem 7 in a manner well understood. Save for the annular housing 3 the mechanism described above presents nothing that is novel.

Hinged at one side of the housing 3 and 75 near the surface of the hull 1 is a scoop plate 8. This scoop plate is provided near its middle with an upstanding slotted ear 9 through which passes a pin 10 secured to the outer end of a bolt 11 which projects 80 from the outer face of valve 5. When the valve is in closed position the scoop plate 8 lies substantially flush with the face of the hull, as shown in solid lines in Fig. 1, preferably bearing against the housing 3 85 as shown. When, however, the valve is in open position the scoop plate is swung outwardly, all as shown in dotted lines in Fig. 1.

In the form of mechanism shown in Fig. 90 2 the housing 3 of the first figure is replaced by a spider or frame 12, which is provided with an annular flange 13 serving as a seat for the valve 14. This valve 14 is likewise provided with a gasket 15 and is operated 95 by means of a valve rod 16. Hinged to an extension of the spider, and near the face of the hull is a scoop plate 17 provided at its inner side with an upstanding slotted ear 18. Extending outwardly from the center of the valve 14 and journaled for reciprocation in a central bushing of the spider is a rod 19. A bell crank lever 20 pivoted upon a pin 21 operatively connects this rod 19 and the scoop plate 17. When the valve 105 is in closed position the scoop plate lies flush with the face of the hull, as shown in solid lines in Fig. 2. When the valve is in open

position the scoop plate is swung outwardly and assumes the position as shown in dotted lines.

So far as the operation of the scoop plate is concerned, the two forms of valve mechanisms shown in the two figures are essentially the same in that in both instances opening of the valve operates to swing the scoop plate outwardly. In Fig. 1, however, 10 this is a direct movement as the valve moves outwardly to open. The valve shown in Fig. 2 moves inwardly to open, but through the instrumentality of bell crank lever 20 this inward movement operates to swing the 15 scoop plate outwardly. With this arrangement the inrush of the water tends not only to force the scoop plate outwardly but to move the valve inwardly and thus further open it. In other words, all of the forces 20 are operating to effect a rapid opening of the valve.

The operation of these devices will be apparent from the foregoing description, it being understood that the direction of movement of the vessel is that indicated by the 25 arrows. It will be readily understood that the very inertia of the water, which operates to retard flooding when using the ordinary simple opening, is now turned to account 30 and made to assist in rapidly filling the tanks. The resistance offered to the water when the scoop plates are thrown outward and in open position, and which is necessary during the flooding operation would, of 35 course, be highly disadvantageous and undesirable when the valve is closed. For this reason it is fundamental in this invention that some means be present for swinging the scoop plate outwardly only when the 40 valve is opened and closing it when the valve is closed. The specific mechanisms shown and described in this application do not exhaust the possibilities and are merely

illustrative of the means whereby the desired end may be attained.

The invention has been illustrated and described in connection with the flooding valves of submarines and it is in this connection that it will probably find its greatest usefulness. It could, however, be used in 45 connection with the discharge valves, where discharge valves separate from the flooding valves, are used, by mounting the scoop plate to open toward the rear. So also rearwardly opening scoops embodying the invention may 50 be used to advantage in connection with 55 vent valves controlling air vent passages leading from the upper part of the ballast tanks, as will be understood.

I claim:

1. A valve mechanism for submarine vessels, comprising the combination of a frame including a valve seat, a valve adapted to be seated thereon, a scoop plate hinged to the frame and designed to close against it when 65 the valve is closed, and means for simultaneously moving the valve inwardly to open it and swinging the scoop plate outwardly.

2. In a submarine vessel, the combination of a hull having a flooding passage therein, 70 a valve designed to open and close the flooding passage, a scoop plate hinged on one side of the flooding passage, and an operative connection between the valve and scoop plate by means of which the latter is swung 75 outwardly when the valve is opened inwardly to direct water through the flooding passage.

3. A flooding valve mechanism for submarine vessels, comprising the combination 80 of an inwardly opening valve, an outwardly opening scoop plate, and means for opening both valve and scoop plate to flood the vessel.

In testimony whereof I affix my signature. 85
HUGO E. GRIESHABER.
